UNITED STATES PATENT OFFICE.

CHARLES WEISS AND GUSTAVE WEISS, OF GLENDALE, NEW YORK.

HAT-RETAINING DEVICE.

1,048,114.

Specification of Letters Patent.

Patented Dec. 24, 1912.

Application filed June 13, 1911. Serial No. 632,955.

To all whom it may concern:

Be it known that we, CHARLES WEISS and GUSTAVE WEISS, both citizens of the United States, and residents of Glendale, Queens 5 county, New York, have invented certain Improvements in Hat-Retaining Devices, of which the following is a specification.

This invention relates to certain improvements in hat retaining devices, such as are 10 particularly designed and adapted for use in connection with ladies' hats, for holding the same in place upon the wearers' heads, and the object of the invention is to provide a device of this general character of a 15 simple and comparatively inexpensive nature, and of a light and compact construction having retaining means of a novel and improved description capable of convenient operation to engage and disengage the hair 20 when the hat is in place upon the head, and adapted, when so engaged, to hold the hat securely in position upon the wearer's head.

The invention consists in certain novel 25 features of the construction, and combinations and arrangements of the several parts of the improved hat retaining device, whereby certain important advantages are attained, and the device is rendered simpler, less expensive, and otherwise better adapted 30 and more convenient for use, all as will be hereinafter fully set forth.

The novel features of the invention will be carefully defined in the claims.

In order that our improvements may be 35 better understood, we will now proceed to describe the same with reference to the accompanying drawings, wherein—

Figure 1 is a view in perspective of the retaining device constructed in accordance 40 with the invention in applied position, the crown of the hat being shown in section for the purpose of better illustration; Fig. 2 is a view partly in top plan and partly in section illustrating the improved retaining 45 device in detail; Fig. 3 is a view partly in section and partly in elevation illustrating the engaging means in operative position, the inoperative position being indicated by dotted lines; Fig. 4 is an enlarged sectional 50 view illustrating a certain detail of construction to be hereinafter referred to; and Fig. 5 is a sectional view taken centrally through the device on the line $a-a$ of Fig. 2.

As herein shown, the improved hat retaining device is provided with a body portion 55 B elongated in form and of a length

adapted to be extended transversely across the crown A of the hat, said body portion including two members C and D which may with convenience be formed from stiff metal 60 wire of similar construction but reversely arranged and having straight stems $1, 1$ which overlap each other at the central part of the elongated body portion whereat they are embraced by an elongated sleeve or barrel 10 within which said straight stems are adapted for independent endwise sliding movement, and also for relative turning movement independently of each other. The bore 11 of the sleeve or barrel is made to 70 receive the overlapping parts of the stems $1, 1$ snugly, for which purpose said sleeve or barrel is made slightly flattened or elongated in cross section, as shown in Fig. 5 75 of the drawings.

The stems $1, 1$ of the members C and D project in opposite directions beyond the opposite ends of the sleeve or barrel 10 and form the opposite ends of the elongated body portion of the device, said oppositely 80 directed ends of the stems being extended in substantial alinement with each other and being provided with tapered portions $1, 2$ which afford points at the extremities of the stems, and rounded shoulders $3, 3$ 85 spaced at suitable distances from said pointed extremities, as clearly indicated in Fig. 4 of the drawings.

$7, 7$ represent heads or caps of such size and shape as to permit of being readily 90 grasped by the fingers, and which may be of any desired fanciful or ornamental design, and are provided, as herein shown, with shanks $6, 6$ having axial bores $5, 5$ adapted to receive the tapered and shouldered outer ends of the body portion, said shanks being split transversely and provided with locking projections $4, 4$ at the opposite sides of their bores 5 so that when the tapered and shouldered ends of the body 95 portion are inserted within said bores 5 , the split shanks will press with some resilience upon the opposite sides of the tapered parts of the stems, and will serve to retain the locking projections $4, 4$ in secure engagement 100 with the rounded shoulders $3, 3$ of the stems, as indicated in Fig. 4. In this way it will be seen that the heads or caps $7, 7$ when in place upon the stems of the members C and D of the body portion will be securely 105 held against accidental displacement by the engagement of their split shanks 6 and their 110

locking shoulders 4, 4 with the tapered parts 2 and shoulders 3, 3 of said stems, while at the same time said heads or caps may be readily detached from the members 5 when desired, after which said members C and D may be slid endwise relatively to one another, so as to shorten the body portion B of the device to such an extent as to permit it to be placed transversely across the interior of the crown A of the hat, whereupon said members C and D may be slid endwise in reverse directions in such a way that the substantially alined pointer extremities thereof are caused to penetrate 10 the opposite side walls of the hat crown and to protrude beyond the same, as clearly shown in Fig. 1.

After the insertion of the device within the crown of the hat as above described, the 20 engagement of the oppositely directed and substantially alined ends of the stems 1, 1 with the opposite side walls of the hat crown affords a secure support for retaining the body portion in position extended transversely across the interior of said crown, and the caps or heads 7, 7 may be applied upon the protruding pointed extremities of the body portion as above set forth, and will serve, when so applied, to hold the device 25 securely in place in the hat against accidental displacement, while upon removal of the caps or heads and reverse endwise movement of the members C and D the device may be quickly and conveniently removed from the hat in order that it may be applied to another hat, if desired.

At their ends opposite to the tapered and pointed portions 2, the stems of the respective members C and D have laterally bent or 40 directed portions 8, 8 pointed at their extremities so as to be adapted to penetrate the hair readily when the hat is placed upon the head, and curved in such a fashion as to afford oppositely directed hook-like portions 45 or prongs spaced apart from each other at the opposite ends of the elongated sleeve or barrel 10, and which are adapted, when the device is in place in the hat, and its members C and D turned or rotated relatively to each 50 other within the sleeve or barrel 10, to play in vertical planes so as to pass in opposite directions through the hair in such a way as to securely engage the same for holding the hat in place upon the head, or to be withdrawn 55 from engagement with the hair so that the hat may be removed from the head, accordingly as the members C and D are turned or rotated in one direction or the other.

60 As herein shown the hook-like portions or prongs 8, 8 have curvatures, as indicated at 9, so that their extremities are adapted to engage the hair at a considerable distance below the sleeve or barrel 10, after which, 65 during the further turning movement of the

members, the hair is drawn upwardly along said curved parts of the prongs, so as to draw the hat downward and retain it securely in position upon the head, while when the members are reversely turned, the curvatures of said prongs causes them to be withdrawn upwardly from the hair without liability of becoming entangled therein. 70

The endwise sliding movement of the members relatively to each other permits the device not only to be conveniently inserted within and withdrawn from the hat, but affords a means whereby the body portion may be shortened or lengthened to adapt it to hats of different sizes, and the heads or 80 caps 7, 7 upon the substantially alined end portions of the device not only prevent accidental displacement of the device, but also afford means for conveniently turning the members independently and simultaneously 85 in reverse directions when it is desired to engage their prongs 8, 8 with the hair or to disengage them therefrom, and also afford means for conveniently moving the members C and D endwise relatively to each other in 90 order that their prongs 8, 8 may be positioned at greater or less distances from one another as may be desired.

From the foregoing description it will be seen that the improved hat retaining device 95 constructed according to our invention is capable of convenient and ready application to the hat and removal therefrom, and is simple in construction and economical to manufacture, and it will also be obvious 100 from the above description that the device is susceptible of considerable modification within the scope of the appended claims without material departure from the principles and spirit of the invention, and for 105 this reason we do not desire to be understood as limiting ourselves to the precise form and arrangement of the several parts, as herein set forth, in carrying out the invention in practice. 110

Having thus described our invention, what we claim as new and desire to secure by Letters Patent is:

1. A device of the character described comprising two members, each of said members having a shank provided with a prong and a sleeve surrounding the shanks of both members, said shanks being capable of longitudinal and rotary movement within the sleeve. 115

2. A device of the character described having members connected for relative endwise movement and for independent rotative movement relatively to each other, and having outer parts adapted to be extended through the side walls of a hat crown, and inner oppositely directed hook-like prongs adapted to be moved one toward or from the other when one member is moved endwise relatively to the other, and adapted, when 125 130

said members are rotated in opposite directions, to pass in opposite directions through the hair.

3. A device of the character described having an elongated body portion adapted to be extended transversely across the interior of a hat crown and including members connected for relative endwise movement and also for independent turning movement 10 relatively to each other, said members having oppositely directed outer extremities extended in substantial alinement with each other and adapted to penetrate the opposite side walls of the hat crown for retaining the body portion in position within the same, and having inner ends provided with oppositely directed hook-like prongs which are adjustable toward and from each other upon 15 endwise movement of one member relatively to the other, and which are adapted, when the members are independently rotated in opposite directions, to play vertically within the hat crown and to pass in opposite directions into and out of the hair.

20 4. A device of the character described having members provided with stems the outer parts of which are adapted to be passed through the sides of a hat crown, and the inner parts of which overlap each other 25 and are connected for independent turning

movement relatively to each other, said inner parts of the stems having oppositely directed hook-like prongs which are adapted, when said stems are rotated in opposite directions, to pass in opposite directions 35 through the hair.

5. A device of the character described having members provided with stems the outer parts of which are adapted to be passed through the sides of a hat crown, and the 40 inner parts of which overlap each other and are adapted for independent turning movement relatively to each other, said inner parts of the stems having oppositely directed hook-like prongs which are adapted, when 45 said stems are rotated in opposite directions, to pass in opposite directions through the hair, and a sleeve embracing the overlapping portions of the stems wherewith said stems are engaged for independent turning 50 movement.

In witness whereof we have hereunto signed our names, in the presence of two subscribing witnesses.

CHARLES WEISS.
GUSTAVE WEISS.
